UNITED STATES PATENT OFFICE.

CAMILLO MACCHIA, OF ARDMORE, PENNSYLVANIA, ASSIGNOR TO THE UNITED STATES FIRE WORKS MANUFACTURING COMPANY, OF CARDINGTON, PENNSYLVANIA, A CORPORATION OF PENNSYLVANIA.

METHOD AND APPARATUS FOR CHARGING TOY TORPEDOES.

Application filed April 6, 1921. Serial No. 458,893.

To all whom it may concern:

Be it known that I, CAMILLO MACCHIA, a citizen of the United States of America, and resident of Ardmore, in the county of Montgomery, State of Pennsylvania, have invented a certain new and useful Improvement in Methods and Apparatus for Charging Toy Torpedoes, of which the following is a true and exact description, reference being had to the accompanying drawings, which form a part thereof.

My invention relates to the manufacture of toy torpedoes and has for its object to provide for charging the torpedo shells with explosive and gravel with great rapidity and, as to the explosive particularly, with great accuracy. In its broader sense my invention consists of a method of handling and charging the shells or casings of the torpedoes but my method involves the use of certain new appliances especially devised for use with it and also invented by me.

My invention will be best understood as described in connection with the drawings which illustrate it and in which—

Figure 1 is a perspective view of a frame for holding the torpedo casings in spaced relation with a charge of said casings in place therein.

Figure 2 is a similar view showing in addition the operation of charging the casings with explosive by means of a special gage measuring and charging scoop.

Figure 3 is a view similar to Fig. 1 but showing the operation of filling the casings with gravel.

Figure 4 is a perspective view of one of the casings.

Figure 5 is a sectional elevation of a casing charged with explosive and gravel.

Figure 6 is a similar view of a torpedo closed and ready for use or shipment, and

Figure 7 is a sectional view of one of the measuring scoops of the gage tool shown in Fig. 2.

A is a frame having a flat bottom A' parallel side walls A², A², and a front wall A³ all of equal height and extending above the bottom A' for a distance preferably equal to the height of a torpedo container. The frame, as shown, also has a rear wall A⁴ which serves as an abutment for springs D, D. The side walls A² are slotted, as shown, at B, B, and these slots serve as guideways

for the ends C' of a follower plate C which is pressed forward by the springs D, D. E, E, are straight flat partition plates fitting in the frame between walls A², A², but movable therein.

F, F, etc. are the casings or containers of the toy torpedoes, preferably made up, as shown, of a cylinder F' of wound and glued paper with a cap F² fitted on its lower end. These containers are placed in the frame A in even parallel rows separated by partitions E and against the rear row rests the plunger C, which exerts sufficient pressure to insure that the rows of containers will be held firmly in the frame.

Having secured the containers in the frame as described I next charge them with explosive powder, using for this purpose the gage measuring and charging scoop made up, as shown, of a series of measuring and charging scoops, G, G, etc. equal in number to the containers held in a parallel row in the frame A and secured on the ends of a series of rods G' which by means of a cross bar G² are secured to a handle G³. The scoops are dipped into the powder and raised each charged with an equal quantity thereof as shown at H in Fig. 7, and then the scoops are brought into alignment with a row of containers and dumped into them as shown in Fig. 2. Each successive row is thus charged in turn.

After all the containers in the frame A are charged with explosive as above described I fill the container with gravel as shown in Fig. 3, a mass of gravel J is swept over the top of the containers in the frame filling all the containers, the surplus gravel being struck or swept off leaving all containers equally charged as shown in Fig. 5 in which K indicates the gravel and I the explosive charge.

After charging the containers, as described, they are removed from the charging frame and closed, preferably as shown in Fig. 6, a cap F² similar to cap F² is placed on the top of the container and glued to it if desired but for the best results the caps are secured in place by a wrapping of glued paper as indicated at F⁴.

The torpedo shown in Fig. 4 is claimed as my invention in my application filed March 15, 1921, Serial No. 452,466.

Having now described my invention,

what I claim as new and desire to secure by Letters Patent, is:

1. The method of charging toy torpedo containers of cylindrical form and uniform size and capacity which consists in placing such containers in a holding frame in parallel rows of equal numbers of containers, dumping explosive powder in measured charges simultaneously into the containers 10 of each row until the containers in the frame have been charged and then further charging the containers with gravel by sweeping a mass of gravel over the top of the frame and its contained rows of cylindrical containers.
2. The method of charging toy torpedo containers of cylindrical form and uniform size and capacity which consists in placing such containers in a holding frame in parallel rows of equal numbers of containers, separating and aligning said parallel rows by straight partitions movable in the frame, pressing the partitions and containers together by elastic pressure to properly grip 25 and position them in the frame, dumping explosive powder in measured charges simultaneously into the containers of each row until the containers in the frame have been charged and then further charging

the containers with gravel by sweeping a 30 mass of gravel over the top of the frame and its contained rows of cylindrical containers.

3. A hand tool for simultaneously charging the containers of toy torpedoes arranged 35 in a spaced parallel row, which consists of a series of measuring scoops each adapted to contain a similar charge of explosive powder, said scoops being laterally separated from each other and rigidly held in 40 a spaced row by attachments extending from their rear ends to a handle.

4. The device for aligning and holding containers of toy torpedoes in parallel rows so that the containers of each row can be 45 simultaneously charged with explosive by a gage scoop tool and so that all the containers can be simultaneously charged with gravel, said device consisting of a frame having a flat bottom and rectangular walls, 50 straight partitions for separating and aligning the rows of containers, said partitions being movable in the frame and a spring actuated plunger plate acting to press the containers and partition plates together and 55 grip them in the frame.

CAMILLO MACCHIA.
